APPLE CORING DEVICE

David L. Dover, Seattle, Wash.

Application March 8, 1957, Serial No. 45,159

Term of patent 7 years

(Cl. D44—29)

Figure 1 is a front elevational view showing my new design.

Figure 2 is a side view of the same.

Figure 3 is a rear elevational view of the same.

Figure 4 a plan view with parts in section taken on broken line 4—4 of Fig. 1.

Figure 5 is a view partly in plan and partly in section taken on broken line 5—5 of Fig. 1.

The essential features of my design reside in the full line portions of the drawings.

I claim:

The ornamental design for an apple coring device, substantially as shown and described.
